UNITED STATES PATENT OFFICE.

ROBERT SUCZEK, OF PHILADELPHIA, PENNSYLVANIA, ASSIGNOR TO C. H. WHEELER
MANUFACTURING COMPANY, OF PHILADELPHIA, PENNSYLVANIA, A CORPOR-
ATION OF PENNSYLVANIA.

AUXILIARY APPARATUS FOR CONDENSERS.

Application filed April 18, 1922. Serial No. 554,513.

To all whom it may concern:

Be it known that I, ROBERT SUCZEK, a citizen of the United States, residing in the city and county of Philadelphia, State of Pennsylvania, have invented certain new and useful Improvements in Auxiliary Apparatus for Condensers, of which the following is a specification.

My invention relates to apparatus for removing liquid or air, or both, as from regions of lower pressure to higher pressure, by ejector action; more particularly, my invention relates to apparatus of the character referred to for removing condensate or air, or both, from a condenser.

My invention resides in apparatus for removing liquid, as condensate, from a receptacle by the ejector action of a motive fluid consisting of components one of which is controllable in response to changes in the quantity of liquid to be removed, and another of which is the discharge of an ejector which raises the pressure of air or other gas.

My invention resides in other features of structure and combination hereinafter described and claimed.

For an illustration of one of various forms my apparatus may take, reference is to be had to the accompanying drawing, which is a vertical sectional view, some parts in elevation, through apparatus embodying my invention.

Referring to the drawing, C represents the body or shell of a condenser, for example, the shell of a surface condenser having the inlet E for the steam to be condensed, as the exhaust steam from a turbine, steam engine, or from any other source. The steam entering at E is condensed in well known manner into water, which is the condensate which is collected in any suitable receptacle, as, for example, the hot well H. O is a port through which air is removed from the interior of the condenser C for producing or maintaining therein high vacuum, as well understood in the art. The port O communicates with the suction of the ejector Z, whose nozzle structure n is supplied with motive fluid, as steam or any other suitable motive fluid, through the pipe connection s.

The ejector Z discharges the mixture of air and motive fluid, as steam, into the cham-

ber X, in which the air has a higher pressure than the condenser C, and the motive fluid steam in the nozzle structure n is of lower pressure than when entering the nozzle structure n. Disposed within the chamber X is the nozzle structure N receiving steam, as live or high pressure steam, from the pipe s² controlled by the valve Y, which is in turn controlled by the float F on the surface W of the condensate in the hot well or other receptacle H. Communicating with the chamber X and extending into the receptacle H is the guide tube or cone B in alignment with the nozzle structure N and in alignment with the diffuser D whose inlet is within the receptacle H and which discharges into the separating chamber L having the air outlet O¹ and the condensate outlet O². The cone or tube B serves as a motive fluid nozzle of a submerged ejector, the motive fluid being that delivered by the nozzle N and the discharge from the ejector Z, or either of them.

With the valve Y open, motive fluid is delivered to the nozzle N, which expands the motive fluid, as steam, to a pressure substantially equal to the pressure in the chamber X, and the motive fluid jet entrains air and steam from the chamber X and delivers it through the cone or tube B into the hot well or receptacle H, where condensation of the steam takes place, producing a vacuum which assists the jet from the tube B in drawing condensate from the receptacle H into and forcing it through the diffuser D and delivering the same at higher pressure into the chamber L, where the air separates and is discharged through the passage O¹ while the condensate is drawn off through the outlet O², the condensate in the chamber L overflowing the partition or weir Q to the discharge outlet O².

As the level W of the condensate falls, the float F falls and moves the valve Y toward closed position, thereby reducing the amount of steam supplied to the nozzle N, and thereby causing the motive fluid issuing therefrom to remove less condensate from the receptacle H. In case the level W falls far enough, the valve Y will be completely closed. In such case the low pressure fluid in the chamber X discharged by the ejector Z may alone serve as motive fluid for the submerged nozzle B to continue

or effect removal of liquid or condensate at low rate. As the level W of the condensate rises again due to accumulation of condensate in the receptacle H, the float F will 5 rise and open the valve Y to proper degree.

When the pressure of the discharge of the ejector Z in the chamber X is sufficiently low while steam is delivered to the nozzle N, the motive fluid of the nozzle N entrains 10 and carries along the fluid from the chamber X. However, when the pressure in the chamber X due to the discharge from the ejector Z is sufficiently high, it too operates 15 as a motive fluid, in conjunction with motive fluid from the nozzle N, in and for the nozzle B for acting upon the liquid or condensate. When the fluid in the chamber X so acts as motive fluid for the nozzle B, it consists of low pressure steam and air, the 20 air, however, being of higher pressure than in the condenser C while the steam is exhausted steam or steam of lower pressure than delivered to the nozzle n of the ejector Z.

Accordingly, as regards the ejector nozzle 25 or cone B, it is supplied with low pressure motive fluid, the same being the exhaust or discharge from the ejector Z; and also higher pressure motive fluid through the nozzle N. The low pressure motive fluid may act 30 alone when the valve Y is closed, or may act in unison with the motive fluid from the nozzle N when the valve Y is open; or the discharge from ejector Z may be entrained and impelled by the motive fluid from the 35 nozzle N into the nozzle B, where the mixture of fluids serves as motive fluid to impel liquid or condensate into the diffuser D, the uncondensable gas or air passing out with the condensate into the chamber L.

40 In general, the ejector delivers the liquid to a higher pressure; when the port O¹ is open to atmosphere, the liquid is delivered from a low pressure in the receptacle or hot well H to substantially atmospheric pressure. With the outlet of gas or air from the port O¹ restricted, the pressure in the 45 chamber L may attain any suitable or desirable degree higher than atmospheric pressure, and the ejector apparatus will deliver the liquid against such higher pressure. In case the low pressure fluid delivered to the chamber X does not contain air or gas, as when low pressure steam from any suitable source is delivered to the chamber X, the 50 gas draw-off port O¹ may be omitted, or the chamber L may be omitted and the diffuser D discharge the liquid directly to any region under high pressure, as into a boiler.

When the low pressure fluid delivered to 60 the chamber X is alone-acting, as when valve Y is closed, to remove liquid from the receptacle H, the amount of liquid delivered from the receptacle H by the ejector B, D may fall below the requirements, in which 65 case the level W of the liquid will rise and

the valve Y will be opened, and the nozzle structure N will assist and increase the rate of delivery of liquid to the amount required. Furthermore, in case there occur fluctuations in the amount or pressure of the fluid 70 delivered to the chamber X, as from the ejector Z, or from any source of exhaust or low pressure steam of variable quantity, the nozzle structure N will automatically be brought to the assistance of the low pressure motive fluid and so effect delivery of liquid at the required rate. In other words, 75 the float F will take different positions in response to fluctuations in the amount or pressure of the motive fluid delivered to the chamber X and in response also to variations in the amount of liquid required to be withdrawn from the receptacle H.

The float F may control the action of the 80 ejector, as by adjusting an adjustable diffuser, or adjustable nozzle, or both.

While the ejectors herein disclosed are of the simple single nozzle type, it will be understood that any suitable forms of ejector may be used, as, for example, those employing a plurality of steam or motive fluid nozzles, or ejectors having annular nozzles and diffusers, and ejectors of the latter type in which the diffuser is disposed outside of 90 and surrounds the annular nozzle which discharges radially into the diffuser, as disclosed in Letters Patent of the United States No. 1,282,595.

The apparatus herein disclosed is disclosed in Letters Patent of the United States 100 No. 1,342,471, granted me June 8, 1920.

What I claim is:

1. The combination with a receptacle for liquid, of an ejector submerged in the liquid in said receptacle and comprising nozzle structure for removing the liquid from said receptacle, a second ejector delivering motive fluid to said nozzle structure, and nozzle structure delivering motive fluid to said first named nozzle structure. 110

2. The combination with a receptacle for liquid, of an ejector submerged in the liquid in said receptacle and comprising nozzle structure for removing the liquid from said receptacle, a second ejector delivering motive fluid to said nozzle structure, and nozzle structure delivering motive fluid and the fluid delivered by said second ejector to said first named nozzle structure. 115

3. The combination with a receptacle for liquid, of an ejector submerged in the liquid in said receptacle and comprising nozzle structure for removing the liquid from said receptacle, a second ejector discharging low pressure elastic fluid to said nozzle structure, and nozzle structure delivering motive fluid to said first named nozzle structure. 120

4. The combination with a receptacle for liquid, of an ejector submerged in the liquid in said receptacle and comprising nozzle 125

- structure for removing the liquid from said receptacle, a second ejector discharging low pressure elastic fluid to said nozzle structure, and nozzle structure delivering elastic motive fluid to said first named nozzle structure. 5. The combination with a receptacle for liquid, of an ejector submerged in the liquid in said receptacle and comprising nozzle structure for removing the liquid from said receptacle, a second ejector discharging low pressure elastic fluid to said nozzle structure, and nozzle structure delivering to said first named nozzle structure elastic fluid 15 having a pressure higher than the pressure of the elastic fluid discharged by said second ejector. 6. The combination with a receptacle for liquid, of an ejector submerged in the liquid in said receptacle and comprising nozzle structure for removing the liquid from said receptacle, a second ejector discharging gas to said nozzle structure, nozzle structure delivering motive fluid to said first named nozzle structure, and a receptacle to which said gas and said liquid are delivered and in which they separate. 7. The combination with a receptacle for liquid, of an ejector submerged in the liquid in said receptacle and comprising nozzle structure for removing the liquid from said receptacle, a chamber with which the intake of said nozzle structure communicates, an ejector discharging into said chamber, and nozzle structure delivering motive fluid and fluid from said chamber into said first named nozzle structure. 8. The combination with a receptacle for liquid, of an ejector submerged in the liquid in said receptacle and comprising nozzle structure for removing the liquid from said receptacle, a chamber with which the intake of said nozzle structure communicates, an ejector discharging into said chamber, nozzle structure delivering motive fluid and fluid from said chamber into said first named nozzle structure, and a receptacle into which said first ejector discharges and in which the liquid separates from gas. 9. The combination with a receptacle for liquid, of an ejector submerged in the liquid in said receptacle and comprising nozzle structure for removing the liquid from said receptacle, a second ejector delivering motive fluid to said nozzle structure, nozzle structure delivering motive fluid to said first named nozzle structure, and means for causing delivery of motive fluid to said second named nozzle structure upon accumulation 60 of said liquid. 10. The combination with a receptacle for liquid, of an ejector submerged in the liquid in said receptacle and comprising nozzle structure for removing the liquid from said receptacle, means delivering low pressure motive fluid to said nozzle structure, nozzle structure for delivering motive fluid to said ejector, and means for causing delivery of motive fluid to said second named nozzle structure upon accumulation of liquid in excess of that removable by said low pressure motive fluid alone. 11. The combination with a receptacle for liquid, of an ejector submerged in the liquid in said receptacle and comprising nozzle structure for removing the liquid from said receptacle, means delivering low pressure motive fluid to said nozzle structure, nozzle structure for delivering motive fluid to said ejector, and means for causing delivery of higher pressure motive fluid to said second named nozzle structure to assist in liquid delivery upon occurrence of too low a rate of delivery of liquid from said receptacle. 12. The combination with a receptacle for liquid, of an ejector submerged in the liquid in said receptacle and comprising nozzle structure for removing the liquid from said receptacle, means delivering low pressure motive fluid to said nozzle structure, nozzle structure for delivering motive fluid to said ejector, and means for causing delivery of higher pressure motive fluid to said second named nozzle structure to assist in liquid delivery upon occurrence of too low a rate of delivery of liquid from said receptacle by said low pressure motive fluid. 13. The combination with a receptacle for liquid, of an ejector submerged in the liquid in said receptacle for removing the liquid from said receptacle, a source of motive fluid for said ejector, a second source of motive fluid for said ejector, and nozzle structure through which motive fluid from said second source is delivered to said ejector. 14. The combination with a receptacle for liquid, of an ejector submerged in the liquid in said receptacle for removing the liquid from said receptacle, a source of low pressure motive fluid for said ejector, a second source of higher pressure motive fluid for said ejector, and nozzle structure through which said motive fluid of higher pressure is delivered to said ejector. 15. The combination with a receptacle for liquid, of an ejector submerged in the liquid in said receptacle for removing the liquid from said receptacle, a source of motive fluid for said ejector, a second source of motive fluid for said ejector, nozzle structure through which motive fluid from said second source is delivered to said ejector, and automatic means controlling delivery of motive fluid from said second source to said nozzle structure in response to occurrence of too low a rate of delivery of liquid from said receptacle. 16. The combination with a receptacle for liquid, of an ejector submerged in the liquid in said receptacle for removing the liquid

from said receptacle, a source of low pressure motive fluid for said ejector, a second source of higher pressure motive fluid for said ejector, nozzle structure through which 5 said motive fluid of higher pressure is delivered to said ejector, and automatic means controlling delivery of motive fluid from said second source to said nozzle structure in response to occurrence of too low a rate of 10 delivery of liquid from said receptacle.

17. The combination with a receptacle for liquid, of an ejector submerged in the liquid in said receptacle for removing said liquid from said receptacle, a chamber with which 15 the intake of the nozzle structure of said ejector communicates, means for delivering motive fluid into said chamber, and a second nozzle structure delivering motive fluid to said ejector.

18. The combination with a receptacle for liquid, of an ejector submerged in the liquid in said receptacle for removing said liquid from said receptacle, a chamber with which the intake of the nozzle structure of said 20 ejector communicates, means for delivering low pressure elastic motive fluid to said chamber, and a second nozzle structure delivering elastic motive fluid of higher pressure to said ejector.

19. The combination with a condenser, of a condensate receptacle, an ejector submerged in the condensate for removing the condensate from said receptacle, means delivering motive fluid to said ejector, and 25 nozzle structure delivering a second motive fluid to said ejector.

20. The combination with a condenser, of a condensate receptacle, an ejector submerged in the condensate for removing the condensate from said receptacle, means for delivering low pressure elastic motive fluid to said ejector, and nozzle structure delivering elastic motive fluid of higher pressure to 30 said ejector.

21. The combination with a condenser, of a condensate receptacle, an ejector submerged in the condensate for removing the condensate from said receptacle, a chamber with which the intake of the nozzle structure 35 of said ejector communicates, means for delivering motive fluid to said chamber, and a second nozzle structure delivering a second motive fluid to said ejector.

22. The combination with a condenser, of a condensate receptacle, an ejector submerged in the condensate for removing the condensate from said receptacle, a chamber with which the intake of the nozzle structure of said ejector communicates, an ejector 40 removing air from said condenser and discharging into said chamber, and means for simultaneously delivering motive fluid to said first named ejector.

23. The combination with a condenser, of a condensate receptacle, an ejector sub-

merged in the condensate for removing the condensate from said receptacle, a chamber with which the intake of the nozzle structure of said ejector communicates, an ejector removing air from said condenser and discharging into said chamber, a source of elastic motive fluid having a pressure higher than the discharge from said second named 70 ejector, and a second nozzle structure through which said higher pressure motive fluid is delivered to said first named ejector.

24. The combination with a condenser, of a condensate receptacle, an ejector submerged in the condensate for removing the condensate from said receptacle, means delivering motive fluid to said ejector, nozzle structure delivering a second motive fluid to said ejector, and automatic means controlling the motive fluid delivered by said nozzle structure in response to occurrence of too 85 low a rate of delivery of condensate from said receptacle.

25. The combination with a condenser, of a condensate receptacle, an ejector submerged in the condensate for removing the condensate from said receptacle, means for delivering low pressure elastic motive fluid to said ejector, nozzle structure delivering elastic motive fluid of higher pressure to said ejector, and automatic means controlling the motive fluid delivered by said nozzle structure in response to occurrence of too low a rate of delivery of condensate from 90 said receptacle.

26. The combination with a condenser, of a condensate receptacle, an ejector submerged in the condensate for removing the condensate from said receptacle, a chamber with which the intake of the nozzle structure of said ejector communicates, means for delivering motive fluid to said chamber, a second nozzle structure delivering a second motive fluid to said ejector, and automatic means controlling the motive fluid delivered by said second nozzle structure in response to occurrence of too low a rate of delivery of condensate from 100 said receptacle.

27. The combination with a condenser, of a condensate receptacle, an ejector submerged in the condensate for removing the condensate from said receptacle, a chamber with which the intake of the nozzle structure of said ejector communicates, an ejector removing air from said condenser and discharging into said chamber, means for 105 simultaneously delivering motive fluid to said first named ejector, and automatic means controlling the motive fluid delivered by said second nozzle structure in response to occurrence of too low a rate of delivery 115 of condensate from said receptacle.

28. The combination with a condenser, of a condensate receptacle, an ejector submerged in the condensate for removing the condensate from said receptacle, a chamber 120

- with which the intake of the nozzle structure of said ejector communicates, an ejector removing air from said condenser and discharging into said chamber, a source of elastic motive fluid having a pressure higher than the discharge from said second named ejector, a second nozzle structure through which said higher pressure motive fluid is delivered to said first named ejector, and automatic means controlling the motive fluid delivered by said second nozzle structure in response to occurrence of too low a rate of delivery of condensate from said receptacle.
29. In combination with a condenser, an ejector withdrawing fluid from said condenser, means delivering independent streams of elastic fluid to said ejector, and means responsive to the rate of production of condensate by said condenser controlling one of said streams.
30. In combination with a condenser, an ejector having a chamber and motive fluid nozzle structure, means delivering independent streams of elastic fluid to said chamber and nozzle structure respectively, and means responsive to the amount of condensate controlling one of said streams.
31. In combination with a condenser, an ejector having a chamber and motive fluid nozzle structure, means for delivering independent streams of steam to said chamber and said nozzle structure, respectively, and means controlled by the condensate from said condenser controlling one of said streams.
32. In combination with a condenser, an ejector removing a fluid from said condenser and having a chamber and motive fluid nozzle structure, means for delivering independent streams of steam to said chamber and nozzle structure, respectively, and means controlled by the condensate from said condenser controlling one of said streams.
33. In combination with a condenser, an ejector for removing condensate and having a chamber and motive fluid nozzle structure, means for delivering independent streams of steam to said chamber and nozzle structure, respectively, and means controlled by the condensate controlling one of said streams.
34. In combination with a condenser, ejector apparatus removing uncondensable fluid and condensate from said condenser, and means controlled by the condensate from said condenser controlling delivery of motive fluid to said ejector apparatus.
35. In combination with a condenser, ejector apparatus having a chamber and motive fluid nozzle structure, an ejector withdrawing uncondensable fluid from said condenser and discharging into said chamber, and means controlled by the condensate from said condenser controlling the supply of motive fluid to said nozzle structure.
36. In combination with a condenser, ejector apparatus comprising a chamber and nozzle structures, the inlet of one of said nozzle structures communicating with said chamber and receiving discharge from another of said nozzle structures, a passage delivering uncondensable fluid from said condenser to said chamber, and means controlled by the condensate from said condenser controlling delivery of motive fluid to said other of said nozzle structures.
37. In combination with a condenser, ejector apparatus comprising a chamber and nozzle structures, the inlet of one of said nozzle structures communicating with said chamber and receiving discharge from another of said nozzle structures, an ejector removing uncondensable fluid from said condenser and discharging into said chamber, and means controlled by the condensate from said condenser controlling delivery of motive fluid to said other of said nozzle structures.
- In testimony whereof I have hereunto affixed my signature this 17th day of April, 1922.
- ROBERT SUCZEK.
